STOVE CONSTRUCTION

Anton K. Weiskittel, Baltimore, Md., assignor to
 Harry C. Weiskittel Co. Inc., Baltimore, Md., a
 corporation of Maryland

Application June 5, 1936, Serial No. 83,799

13 Claims. (Cl. 126—339)

My invention relates to stove construction, and more particularly to the construction of ovens for cooking stoves.

Heretofore it has been difficult to inspect food being cooked in the ordinary cooking stove ovens, as it was necessary to slide out the shelf on which the food was resting by manual manipulation. The shelf was of course hot and had to be handled with a protective device for the hand. At the same time there was danger of burning the hands, as well as inconvenience in time consumed in making the inspection since the shelves with their heavy weight of food upon them were often hard to move.

15 There was further danger that the shelf would be pulled out too far, allowing the food to be spilled on the floor. These and other inconveniences and disadvantages of former constructions are in a large measure overcome by the present construction.

It is an object of my invention to devise an oven wherein the food on the shelves can be readily inspected at all times during the cooking operation.

25 A further object of the invention is to devise a construction which will move out the shelf or support on which food is resting so that it will project beyond the front of the oven and can be readily inspected.

30 Yet another object of the invention is to provide a construction which will accomplish the above, which is simple, sturdy and inexpensive to manufacture.

A still further object of the invention is to 35 provide a construction which is easy to repair and replace and in which there are few operating parts.

With these and other objects in view, which may be incident to my improvements, the invention consists in the parts and combinations to be hereinafter set forth and claimed, with the understanding that the several necessary elements comprising my invention may be varied in construction, proportions and arrangement, 45 without departing from the spirit and scope of the appended claims.

In order to make my invention more clearly understood, I have shown in the accompanying drawings means for carrying the same into practical effect without limiting the improvements in their useful applications to the particular constructions, which, for the purpose of explanation, have been made the subject of illustration.

In the drawings:

55 Figure 1 is a perspective view of a stove show-

ing my pull out oven construction in the pulled out position;

Fig. 2 is a perspective view of the same stove with the oven door shut and the pull out construction concealed on the inside of the stove;

5

Fig. 3 is a sectional view taken through the oven and the pull out construction showing the position of the parts in the pulled out position;

Fig. 4 is a view taken along the line 4—4 of Figure 3, looking in the direction of the arrows;

10

Fig. 5 is a view taken along the line 5—5 of Figure 3, looking in the direction of the arrows;

Fig. 6 is a detail perspective view of one of the holding members, and a portion of the sliding support;

15

Fig. 7 is a view taken along the line 7—7 of Figure 5, looking in the direction of the arrows;

Fig. 8 is a detail perspective view of a modification of the sliding support member equipped with a novel form of shelf support frame.

20

Referring to the drawings I have shown a stove 1 having an oven 2 having side oven walls 3 and 4. On the side oven walls are grooved tracks 5 in which are adapted to slide shelves 6 which are generally of the usual open bar construction. The oven is provided with a top 7. The side walls 3 and 4 and the top 7 are insulated, as indicated in the drawings, with some suitable insulating material. The lower portion of the side wall 4, which I have designated by 30 the numeral 8, is not insulated, as it abuts against a compartment 9 in which is adapted to be placed food to be kept hot.

The oven is provided with a metallic sheet bottom 10 which is provided with airholes, not 35 shown. There is placed in the oven a heating element of the usual construction 11, which lies under a baffle plate 12 composed of a lower metallic sheet member 13 and an upper metallic sheet member 14. The upper metallic sheet 40 member 14 is riveted or otherwise suitably attached to an insulated rear wall 15 of the oven 2, and also at the front end to a front wall construction 16, which comprises a relatively narrow strip across the front of the oven.

45

There is provided an aperture 17 in the front wall in which is adapted to slide a sliding frame 18 having an insulated front wall 19 which fits within the aperture 17 of the oven front wall 16 when the sliding support 18 is in the closed position. Hinged on the front wall 16 is an insulated oven door 20.

50

Attached at one side of the front wall 19 of the sliding support 18 is an upstanding handle support 21 which substantially at its mid-point car-

55

ries a handle 22. The handle 22 can be grasped by the hand of the user and the sliding support 18 either slid into the oven or pulled out. In the inner position the door 20 is closed, as shown 5 in Figure 2. In the outer position the sliding support 18 carries with it the shelf 6.

Carried at the back of the sliding support 18 are two members 23 which may be fastened by bolts 24 to the inside of a tray 25', which is fastened at its front end to the front 19 of the sliding support 18. These two members 23 are of flat metal and are provided with forwardly extending arms 25. The members 23 are notched, as indicated at 26. A roasting oven bottom 27 15 of sheet metal has a downturned flange 28 which fits into the notches 26 of the members 23, and the downturned flange 29 which fits over the end of the arms 25. The bottom 27 of the roasting oven can be used to support food being 20 cooked, as also can any of the shelves 6.

Holding members 30 are attached by bolts 31 to the members 23. The holding members comprise upstanding arms 32 having inwardly projecting lugs 33 which fit over slots 34 formed 25 in sliding lock members 35. The lugs 33 are provided with enlarged heads which prevent them from coming out of the slots 34. The lugs 33 30 may be riveted in place on the arms 32, or otherwise suitably attached.

Each sliding lock member 35 is provided with notches 36 and downwardly projecting catches 37 which are adapted to fit over the rearmost wire of one of the trays 6 to hold the tray 6 securely to each holding member 30. When the 35 sliding lock members 35 are in the raised position, however, the catches 37 do not engage the rearmost wire of the shelves 6, and the shelves 6 may freely slide in the grooved tracks 5.

Ordinarily the pull of gravity on the sliding lock members 35 holds them in the down position, as indicated in Figure 3. In the rearmost position, however, of the sliding support 18, rollers 38 mounted on the sliding lock members 35 engage cams 39 affixed to the rear wall 15 of the oven 2. These rollers 38 contacting with cam surfaces on cams 39 raise the sliding lock members 35, releasing the rearmost wire of each shelf or tray 6. In this position of the parts, when the front door 20 is down each shelf or tray 50 6 can be slid in its grooved tracks 5 by manual manipulation so that a particular shelf may be moved with relationship to any other particular shelf. In the out position of the sliding support 18 however, all of the shelves are securely held 55 in position by the sliding lock members 35 and the shelves are moved in unison.

For the purpose of simplicity and illustration, I have shown in the drawings but one shelf 6 in place. It is to be understood, however, that there may be a plurality of shelves, and that the pairs of opposed grooved tracks 5 are each supposed to support a tray or shelf if desired. This construction enables the trays or shelves to be used 60 as desired, and their number varied as well as the distance between them to suit the exigencies of the cooking operation.

In order that the sliding frame 18 may be readily slid into the oven or pulled out, I have 70 shown a frame member 40 mounted in the bottom of the oven carrying at its end track members 41 against which are adapted to bear rollers 42 carried by supports 43, carried by the rear wall of the tray 25'. Mounted in the upper turned ends 44 of the frame 40 are rollers 45

which bear against tracks 46 carried by the bottom of the tray 25'.

This construction gives a cantilever supporting effect to the sliding support 18, the tray sliding on rollers 45 and being held from tipping by the action of rollers 42, see Figure 3. This construction permits of great ease in pulling in and out the sliding support 18.

In order to strengthen the tray 25', I have shown bracing elements 47 which are suitably 10 attached by bolts 48 to the sides of the tray 25'.

In order to prevent the support from being pulled out too far, I have shown downwardly curved arresting surfaces 49 formed on the arms 25 of the members 23. These arresting surfaces 15 contact with the upper portion of the front 16 of the oven in the out position, see Figure 3, thus preventing the sliding frame 18 from being pulled out too far.

From the above description it will be seen that 20 all that is necessary to do is to pull the front door 20 in the down position, grasp the handle 22 and pull out the oven, including the bottom 27 and the trays 6. The extent to which this structure can be pulled out of the oven is governed by 25 the position of the arresting surfaces 49 on the arms 25. When the sliding frame 18 is in the rear position the trays or shelves are freed from the sliding lock members 35, and can be moved relative to each other by manual manipulation. 30

In Figure 8 I have shown a modification in which there are mounted on the members 23 of the sliding frame 18 shelf support frames 50 carrying on their inner surfaces grooved tracks 51 in which the shelves 6 are adapted to slide. 35 The shelf support frames 50 are provided with lower curved surfaces 52 in order to lighten the construction. This construction permits of relative movement of the trays 6 in the "out position" of the sliding support 18 since there is no locking 40 of the trays 6 in any definite position, the trays 6 merely traveling with the shelf support frames 50. This construction presents some advantages in permitting movement of the trays 6 when the sliding support 18 is pulled out, which is different from the operation of the construction previously described where the trays or shelves 6 can only be changed in position when the sliding support 18 is in the innermost position, and the cams 39 have raised the sliding lock members 35 50 through their action against the rollers 38 carried by the sliding lock members 35.

While I have shown and described the preferred embodiment of my invention, I wish it to be understood that I do not confine myself to the precise details of construction herein set forth, by way of illustration, as it is apparent that many changes and variations may be made therein, by those skilled in the art, without departing from the spirit of the invention, or exceeding the scope 60 of the appended claims.

I claim:

1. A stove construction comprising an oven, a source of heat in the oven, a sliding frame in the oven which is adapted to support food to be cooked, 65 lying above and below said source of heat, a handle attached to the bottom part of said frame outside of the oven whereby the sliding frame may be moved outwardly from the oven to inspect food being cooked.

2. In a stove construction, the combination of an oven, a sliding frame therein, holding members on the back of the sliding frame, shelves adapted to be held by the holding members, and means to move the sliding frame into and out of the 70

oven carrying with it said shelves, and means positioned on the rear wall of the oven to release the shelves from the holding members when the sliding assembly is moved into its rearmost position in 5 the oven.

3. In a stove construction, an oven, a front piece therefor, a movable frame in the oven to support food being cooked, and means to slide the frame forward so that the food in the oven can be 10 inspected, and curved arresting surfaces carried by the movable frame having a progressively increasing pressure on the front piece to prevent movement of the movable frame beyond a predetermined position.

15 4. A stove construction comprising an oven, a source of heat in the oven, a sliding frame in the oven which is adapted to support food to be cooked lying above and below said source of heat, a handle connected to the bottom part of said 20 frame outside of the oven whereby the sliding frame may be moved outwardly from the oven to inspect food being cooked, shelves carried by the sliding frame, and means to release the shelves when the frame is in the rearmost position.

25 5. In a stove construction, the combination of an oven, a sliding frame therein, holding members on the back of the sliding frame, shelves adapted to be held by the holding members, means to move the sliding frame into and out of the 30 oven carrying with it said shelves, grooved tracks on the inside of the oven on either side thereof in which the shelves are adapted to slide, and cam means to raise the holding members in their rear position whereby individual shelves can be moved 35 in their tracks.

40 6. In a stove construction, an oven, a source of heat in the oven, a sliding base adapted to fit in the oven below said source of heat, a frame mounted upon the sliding base adapted to support food above said source of heat when said 45 frame and base are positioned in the oven, said frame and base adapted to slide outward as a unit from the oven so that food can be inspected.

7. In a stove construction, an oven, a source 45 of heat in the oven, a sliding base adapted to fit in the oven below said source of heat, a frame mounted upon the sliding base adapted to support food above said source of heat when said frame and base are positioned in the oven, said 50 frame and base adapted to slide outward as a unit from the oven so that food can be inspected, and means to prevent movement of said frame and base beyond a predetermined point.

55 8. A stove construction comprising an oven, a source of heat in the oven, a sliding base in the oven below said source of heat, a frame mounted upon the sliding base adapted to support food

above the level of said source of heat, a handle connected with said base outside of the oven whereby the sliding base and frame may be slid into and out of the oven at will, and means carried by said frame to prevent movement beyond a predetermined position. 5

9. A stove construction comprising an oven, a source of heat in the oven, a sliding base in the oven below said source of heat, a frame mounted upon the sliding base adapted to support food 10 above the level of said source of heat, an upstanding handle support attached to said sliding base, a handle on said handle support outside of the oven whereby the sliding base and frame may be slid into and out of the oven at will. 15

10. A stove construction comprising an oven, a source of heat in the oven, a sliding base in the oven below said source of heat, a frame mounted upon the sliding base adapted to support food above the level of said source of heat, an upstanding handle support attached to said sliding base, a handle on said handle support outside of the oven whereby the sliding base and frame may be slid into and out of the oven at will, and arresting means carried by said frame to prevent 20 movement beyond a predetermined position. 25

11. In a stove construction, the combination of an oven, a sliding frame therein, shelves, catches on the back of the sliding frame having a dogging action adapted to grip said shelves, means positioned on the rear wall to release said catches, and means to move the sliding frame into and out of the oven carrying with it said shelves. 30

12. A stove construction comprising an oven, a sliding frame in the oven, a roasting oven 35 bottom connected to the sliding frame, said frame and the roasting oven bottom adapted to slide out from the oven as a unit, an upstanding handle support attached to the lower part of said frame at the outside of the oven, a handle on the upstanding handle support, whereby the said frame and roasting oven bottom may be slid into and out of the oven at will, and arresting means carried by said frame to prevent movement beyond 40 a predetermined position. 45

13. In a stove construction, the combination of an oven, a sliding frame therein, holding members on the back of the sliding frame, shelves adapted to be held by the holding members, means to move the sliding support into and out of the oven, carrying with it said shelves, grooved tracks on the inside of the oven on either side thereof in which the shelves are adapted to slide, and cam means positioned in the oven to release the shelves from the holding members when the 50 frame is within said oven. 55

ANTON K. WEISKITTEL.
